(57) **CLAIM**

The ornamental design for a hand tool, as shown and described.

DESCRIPTION

FIG. 1 is a perspective view of a hand tool showing our new design;

FIG. 2 is a top view thereof;

FIG. 3 is a bottom view thereof;

FIG. 4 is a right side view thereof;

FIG. 5 is a left side view thereof;

FIG. 6 is a rear view thereof;

FIG. 7 is a front view thereof;

FIG. 8 is a perspective view thereof in an alternate position;

FIG. 9 is a top view of FIG. 8;

FIG. 10 is a bottom view of FIG. 8;

FIG. 11 is a right side view of FIG. 8;

FIG. 12 is a left side view of FIG. 8;

FIG. 13 is a rear view of FIG. 8; and,

FIG. 14 is a front view of FIG. 8.

The dashed lines are for illustrative purposes only and form no part of the claimed design.
